(57) **CLAIM**

The ornamental design for a glasses holder apparatus as shown and described.

DESCRIPTION

FIG. 1 is a front view of a glasses holder apparatus showing my new design;

FIG. 2 is a left side view thereof;

FIG. 3 is a top view thereof;

FIG. 4 is a rear view thereof;

FIG. 5 is a right side view thereof;

FIG. 6 is a bottom view thereof;

FIG. 7 is a front-bottom perspective view thereof;

FIG. 8 is a rear-top perspective view thereof; and,

FIG. 9 is an alternative rear-top perspective view thereof.
